FUEL SYSTEM

Emil O. Wirth, South Bend, Ind., assignor to
 Bendix Aviation Corporation, South Bend, Ind.,
 a corporation of Delaware

Application October 19, 1944, Serial No. 559,434

4 Claims. (Cl. 261—37)

1

This invention relates to fuel systems for internal combustion engines and the like and more particularly to pressure fuel systems wherein the fuel is delivered to the carburetor or engine under superatmospheric pressure and contains subject matter in common with the following applications: Leibing and Fageol, Serial No. 533,848, filed May 3, 1944, in which is disclosed a fuel supply system having a movable flow responsive member in the induction passage for controlling the discharge of fuel thereinto from a constant pressure supply; Wirth, Serial No. 555,077, filed September 21, 1944, now abandoned.

The above Wirth application teaches a pressure fuel system wherein the fuel to air ratio of the fuel mixture is varied by varying the effective pump delivery pressure of the fuel to the carburetor, the pump being of the constant delivery type. The present invention provides an improved pressure fuel system of this type.

Another object of the present invention is to provide a fuel system of this character of simple construction and having improved performance and economy.

A further object of the invention is to provide a device of this character adapted to control the fuel pressure in accordance with at least one engine operating variable.

A still further object is to provide means for modifying said pressure in accordance with barometric pressure.

The characteristics and advantages of the invention are further sufficiently referred to in connection with the following detailed description of the accompanying drawing which represents a preferred embodiment thereof. After considering the example, skilled persons will understand that many variations may be made without departing from the principles disclosed, and I contemplate the employment of any structures, arrangements, or modes of operation that are properly within the scope of the appended claims.

The accompanying drawing is a diagrammatical view showing a fuel system as a whole wherein the present invention is embodied.

While the present invention is shown and described in connection with a downdraft carburetor having a movable flow responsive member in the induction passage for controlling the inflow of fuel to said passage, it is to be understood that the present invention may be used in other types of fuel systems, such as those employing other flow responsive means, which means may include diaphragms or the like for controlling the metering of the fuel. The invention may also be used

in connection with carburetors of the updraft or horizontal delivery type.

The fuel system, as shown, comprises the usual fuel tank 10 connected by a conduit 12 to a fuel pump 14 of known construction. The pump may be of the diaphragm type commonly used on present day installations, but for simplicity is shown as a gear pump having a by-pass 16 controlled by a pressure responsive valve 18 set for a predetermined pressure. Whatever the type of pump, it should supply fuel to the carburetor at a substantially constant pressure and should preferably prevent flow through the line when the engine is not operating. An outlet line 20 leads from the pump to a pressure regulator indicated generally at 22, and thence is conveyed by a conduit 24 to a separating chamber, not shown herein but preferably of the character of that shown and described in the above Leibing and Fageol application, there being a return line 26 which conveys excess fuel, together with any vapor which may be present in the line, back to the tank 10. The return line 26 is preferably provided, at its point of connection with the chamber, with a restriction (shown in said Leibing and Fageol application) of such size as to permit pressure to be built up in the chamber. From the separating chamber fuel is conveyed to a nozzle 28 of the carburetor, indicated generally at 30, and the discharge of fuel into the induction passage is controlled by a fuel valve 32 controlled through a lever 34 in accordance with certain engine operating conditions, which as shown herein and described hereinafter, comprises means responsive to fluid flow through the induction passage of the carburetor. This fluid flow responsive means is adapted to so control the flow of fuel into the induction passage as to proportion said fuel in accordance with the mass air flow through said induction passage.

The carburetor generally

The carburetor 30, as illustrated in the drawings, is substantially the same in construction and operation as that shown in the Leibing and Fageol application above referred to, and will therefore be but briefly described herein. This carburetor comprises an induction passage including an air inlet portion 36 and a mixture outlet 38. Within the inlet portion 36, and anterior to the throttle, is a vane or valve 40 fixed to an offcenter shaft 42 so that flow of the air in the induction passage tends to rotate the vane and shaft in a counterclockwise direction. A spring, not shown, yieldingly urges the vane in

the closing direction. The mixture outlet 38 is controlled by a throttle valve 44. Secured to the vane is a cam 54 operably engaging a roller 56 mounted on the lever 34 which has an end 58 adapted to engage the stem 59 of said valve 32. The valve 32 is adapted to be moved in the opening direction by said lever and is urged in the closing direction by a spring 60, it being noted that the pressure of fuel on the valve has little or no effect on the action of said valve, that is the valve is operable substantially independent of fuel pressure thereon.

The carburetor may also include such other elements, not shown herein but fully disclosed in the above Leibing and Fageol application, as are compatible with the present arrangement, said means being adapted to variably control the characteristics of the fuel mixture under various predetermined operating conditions.

Fuel regulator

Suitable means for regulating or controlling the pressure of the fuel delivered to the carburetor induction passage is provided and is interposed in the fuel line between the pump 14 and the carburetor. The regulator comprises a body having a central casing member 64 which includes an inlet 65 connected with the conduit 20 from the fuel pump and an outlet 66 connected with the conduit 24 to the carburetor. A hollow end member 67 is secured to one side of the central member 64 by any suitable means such as screws 68, and a second hollow member 70 secured to the opposite side of the central member 64 by screws 72. A flexible diaphragm 74 is secured between the casing members 70 and 64 thereby separating the interior of the regulator into two chambers, 76 and 78. The former chamber is a fuel chamber and the latter is connected with a venturi 80 in the induction passage by a conduit 82, which may, if desired, be provided with a calibrated restriction 84. Within the chamber 76 is a valve, indicated generally at 86, which is connected to the inlet 65 by conduit 88. The valve includes a seat 90 adapted to be engaged by a movable valve member 92 connected to the diaphragm 74 by a valve stem 94. A spring 100 is disposed in the chamber 78 and is adapted to react between the diaphragm 74 and a spring retainer 102. The spring retainer has a central recess in which is received the tapered end 104, a screw 106 screwed into the adjacent end wall 108 of the member 70. By turning the screw inwardly or outwardly the tension of the spring is manually varied and a lock nut 110 is provided for locking the screw 106 in adjusted positions.

Fuel under substantially constant pump pressure, entering the regulator by way of the inlet 65, passes through valve 86 and into the chamber 76 and urges the diaphragm downwardly in opposition to the upwardly exerted force of spring 100, so that the valve 86 is controlled primarily by the pressures on opposite sides of the diaphragm, and the effective force urging the valve 86 closed determines the fuel pressure posterior to the regulator. Further, with the above arrangement the pressure of fuel to the carburetor may be varied by varying one of the above pressures on the diaphragm 74.

Barometric control means

Means for varying the suction transmitted from the venturi 80 to the chamber 78 is provided and, as shown herein, comprises a pressure re-

sponsive device indicated generally at 120. This device comprises a casing 122 within which an expansible bellows 124 is disposed. The bellows is attached at one end to a reservoir 126 screwed into the upper end of the casing 122. The bellows is adapted to be filled with a liquid and the reservoir is partly filled with such liquid, the upper portion of the reservoir being filled with a gas and communication is provided between the reservoir and the bellows by a calibrated passage 128 which is adapted to so restrict the flow of liquid between the reservoir and the bellows as to damp fluctuations thereof. A conduit 130 leads from the air entrance 36 of the carburetor to the interior of the casing 122 and a passage 134 leads from the interior of the casing 122 to a passage 136 controlled by a valve 138 secured to the free end of the bellows, the valve member 138 having a tapered point 140 adapted to cooperate with a valve seat 142 of said passage 136. A conduit 144 connects the passage 136 and the conduit 82. With this arrangement air may be bled from the air inlet 36 to the conduit 82 for varying the suction transmitted from the venturi 80 to the chamber 78 of the regulator unit, the quantity of air thus bled being controlled by atmospheric pressure or pressure at the air inlet which is transmitted to the interior 132 of the casing 122.

Should the present device be installed on an aircraft the fuel mixture will be maintained at the proper ratio as the aircraft changes altitude due to the barometric control. As the aircraft rises, for example, the pressure in the inlet 36 will decrease and result in a decrease of pressure in the chamber 132 of the barometric control unit 120 whereupon the bellows will expand and reduce the amount of air bled to the conduit 82 so that an increase in suction will be transmitted from the venturi to the chamber 78 and result in increasing the closing force on the valve member 92 which in turn will result in a decrease in the pressure of fuel posterior to the regulator to compensate for the reduction in the density of the air being taken into the induction passage of the carburetor. When the aircraft descends into denser atmosphere the operation of the device will be the reverse of that above described and an increase in the supply of fuel will be effected.

It is thought that the invention and many of its attendant advantages will be understood from the foregoing description and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a fuel system for an internal combustion engine: an induction passage having an air inlet and a mixture outlet controlled by a throttle valve; a movable member anterior to the throttle and adapted to be actuated by air flow in the induction passage; a fuel nozzle; a substantially constant delivery fuel pump; means connecting said pump and said nozzle; valve means controlled by the movable member for controlling the delivery of fuel to the induction passage, said valve being substantially unresponsive to fuel pressure; regulating means for varying the ratio of fuel to air uniformly to the engine by modifying the pressure of fuel anterior to the fuel valve; a venturi in the induction passage anterior to the

throttle; a connection between the venturi and the regulator means whereby the latter is controlled in accordance with Venturi suction; means for bleeding air from the air inlet of the induction passage to said connection for modifying the Venturi suction; and means responsive to barometric pressure for controlling the bleed means.

2. In a fuel system for an internal combustion engine: an induction passage having an air inlet and a mixture outlet controlled by a throttle valve; a movable member anterior to the throttle adapted to be actuated by air flow in the induction passage; a fuel nozzle; a source of fuel at a substantially constant pressure; a conduit connecting said source and said nozzle, including a metering orifice therein; a valve means controlled by a movable member for controlling the effective area of the metering orifice; regulating means for varying the ratio of fuel to air for the engine by modifying the pressure of the fuel anterior to the fuel valve; a venturi in the induction passage anterior to the throttle; a connection between the venturi and the regulator means whereby the latter is controlled in accordance with Venturi suction; and means for bleeding air into said connection for modifying the Venturi suction.

3. In a fuel system for an internal combustion engine having an induction passage with a venturi and a throttle valve therein; a vane anterior to the throttle adapted to be actuated by air flow in the induction passage; a fuel nozzle; a source of fuel at a substantially constant pressure; a conduit connecting said source with said nozzle, including a metering orifice therein; a valve controlled by the vane for controlling the effective area of the metering orifice; a regulating means for varying the ratio of fuel to air by modifying the pressure of the fuel anterior to the fuel valve, said regulating means comprising a valve member; a chamber for fuel downstream from said member; an air chamber; a movable wall separating said chambers; a passage connecting said air chamber with the venturi, said movable wall being connected to said valve member and adapted to actuate said member in accordance with the differential in pressure between said chambers; and a yieldable means urging said movable wall in the direction to open said valve member.

4. In a fuel system for an internal combustion engine having an induction passage with a venturi and a throttle valve therein; a vane anterior to the throttle adapted to be actuated by air flow in the induction passage; a fuel nozzle; a source of fuel at a substantially constant pressure; a conduit connecting said source with said nozzle, including a metering orifice therein; a valve controlled by the vane for controlling the effective area of the metering orifice; a regulating means for varying the ratio of fuel to air by modifying the pressure of the fuel anterior to the fuel valve, said regulating means comprising a valve member; a chamber for fuel downstream from said member; an air chamber; a movable wall separating said chambers; a passage connecting said air chamber with the venturi in the induction passage, said movable wall being connected to said valve member and adapted to actuate said member in accordance with the differential in pressure between said chambers; a yieldable means urging said movable wall in the direction to open said valve member; an air bleed for modifying the Venturi pressure in said air chamber; and a means responsive to barometric pressure for controlling said air bleed.
